DES. 16.978

UNITED STATES PATENT OFFICE.

JAMES H. FLINN, OF SCHENECTADY, NEW YORK.

DESIGN FOR A WHISK-BROOM HOLDER.

SPECIFICATION forming part of Design No. 16,978, dated November 9, 1886.

Application filed June 17, 1886. Serial No. 205,490. Term of patent 7 years.

To all whom it may concern:

Be it known that I, JAMES H. FLINN, of Schenectady, in the county of Schenectady and State of New York, have invented and produced a new and original Design for Whisk-Broom Holders, of which the following is a specification, reference being had to the accompanying photographs, forming part thereof.

The accompanying photographic representations show several applications of my design in connection with various styles of ornamentation of the whisk-broom case and its back.

The leading feature of my design consists in 15 horns or horn-shaped ornaments applied to the whisk-broom case or forming part thereof, the horns or horn-shaped ornaments being applied to the case or holder in such a manner that when viewed in front elevation they project 20 from the sides thereof and present an appearance similar to the horns projecting from the back.

In Figure 1, *a* represents the back of the case, which is of a general rectangular form, 25 with ornamental edges. *b* is the case, holder, or pocket proper for the broom, as shown, and *cc* are the horns or horn-shaped ornaments projecting from the sides of the case. Transversely of the case is a swell enlargement or molding, *d*, 30 raised above the surface of the case and continuous with the bases of the horns.

Fig. 2 represents the leading feature of the design applied to a number of different styles of whisk-broom cases or holders.

I claim—

1. The design for a whisk-broom holder herein shown and described, the same consisting of the flattened case with horns or horn-shaped projections extending laterally from the sides of the case. 35

2. The design for a whisk-broom holder herein shown and described, the same consisting in the case, horns or horn-shaped projections extending laterally from the sides of the case, and a swell or enlargement continuous 40 with the bases of the horns across the face of the case. 45

3. The design for a whisk-broom holder herein shown and described, the same consisting in the case *b*, an ornamental back, horns 50 or horn-shaped ornaments *c c*, projecting from the sides of the case, and a swell or enlargement, *d*, across the face of the case continuous with the bases of the horns. 55

In testimony that I claim the foregoing as my invention I have hereunto subscribed my name this 11th day of June, 1886.

JAMES H. FLINN.
